UNITED STATES PATENT OFFICE.

GUSTAF A. PERSSON, OF MOUNT CLEMENS, MICHIGAN, ASSIGNOR TO THE PERSSON LABORATORIES, OF MOUNT CLEMENS, MICHIGAN, A CORPORATION OF MICHIGAN.

CONTAINER FOR STERILE LIQUIDS.

1,417,561.

Specification of Letters Patent. Patented May 30, 1922.

Application filed November 5, 1921. Serial No. 513,214.

To all whom it may concern:

Be it known that I, GUSTAF A. PERSSON, a citizen of the United States of America, residing at Mount Clemens, in the county 5 of Macomb and State of Michigan, have invented certain new and useful Improvements in Containers for Sterile Liquids, of which the following is a specification, reference being had therein to the accompanying drawings.

This invention relates to a container designed to facilitate the storing and dispensing of sterile liquids.

The principal object of the invention is 15 to provide a device in which liquids intended for hypodermic injection may be preserved in an aseptic condition and from which doses may be withdrawn without exposing the contents to infection.

20 A further object of the invention is to provide a container having a stopper of a material permitting the introduction of a hypodermic needle therethrough, whereby liquid may be withdrawn from the container, means 25 being provided for sterilizing the stopper and for maintaining it sterilized until the next withdrawal between successive withdrawals of liquid.

A further object of the invention is to 30 provide a stopper having means by which a limited portion of the contents of a container may be withdrawn from the main body of the liquid and held in position for ready withdrawal by a hypodermic needle 35 without subjecting the portion so withdrawn to infection.

Other and further objects will appear in connection with the accompanying description, reference being had to the accompanying drawing, in which—

40 Figure 1 is a vertical section through a preferred embodiment of my invention, the protecting cap being shown in its closed position;

45 Fig. 2 is a corresponding section illustrating the protecting cap partially open, with a portion of the liquid separated from the main body in position for withdrawal by the needle of a hypodermic syringe, and

50 Fig. 3 is an elevation of the device, the cap being completely closed.

The device consists of three essential parts, a glass container 1, screw-threaded at its neck as indicated at 2, a hollow rubber stopper 3 and a metal protecting cap 4 screw

threaded to engage the neck of the bottle as indicated at 5.

The mouth of the bottle is preferably made with a slight taper and a correspondingly tapered rubber stopper 3 is provided of a 60 size to fit snugly within the neck of the bottle 1. The stopper 3 is made hollow, the chamber 7 therein having its outer portion beyond the neck of the bottle made with comparatively thin walls.

65 In the center of the base of the stopper is a circular opening 8 permitting liquid to flow from the container into the bulbular portion of the stopper when the bottle is tilted upon its side. If the bottle is completely inverted, all the air within the stopper will escape, the bulbular portion then being completely filled with liquid.

70 A glass ball 9 acts as a valve preventing the liquid from flowing back into the bottle when the container is again placed in a vertical position. The screw cap 4 has a slot 75 10 formed within the screw-threaded portion thereof and when the cap is screwed down tight upon the bottle, a shoulder 11 on the cap engages tightly against the top of the bottle and the slot 10 is closed, since in this position of the cap the slot lies opposite a portion of the glass neck. If the screw cap is unscrewed, a portion of the thin walled 80 bulbular part of the stopper will be exposed opposite the slot 10, permitting a hypodermic needle 12 to be inserted through the rubber wall of the stopper into the liquid contained therein. By a proper manipulation 85 of the syringe and needle, substantially the entire dose of liquid contained within the stopper may be withdrawn and when the needle is removed, the punctured rubber wall closes, completely sealing the perforation 90 made by the needle.

95 Within the hemispherical top of the metal cap is a layer of absorbent felt 13, saturated with an antiseptic material. In the act of screwing the cap into closed position and in 100 unscrewing the cap when arranging the container for removal of a dose of the liquid, this antiseptic pad of felt will be brought into intimate contact with the entire upper surface of the bulbular portion of the stopper, thus acting to sterilize the outer surface.

105 The operation of the device will be apparent from the above description. The bottle is first tilted to allow liquid to flow into the rubber stopper and if desired the container 110

may be completely inverted so that all the air within the stopper will pass out and when the bottle is tilted back into a vertical position the glass ball valve will seat itself within the port 8, leaving the bulbular portion of the stopper filled with the liquid.

The screw cap will then be rotated to unscrew it from the neck of the bottle, the felt lining of the cap wiping the outer surface 10 of the stopper with its antiseptic material and when the slot 10 is in a position opposite a part of the thin wall of the stopper which has not previously been punctured, a sterile hypodermic needle may be thrust 15 through the rubber wall of the stopper and the liquid contained therein may be withdrawn in part or altogether. The hypodermic needle is then withdrawn; the screw cap is again rotated to bring the antiseptic 20 lining into close contact with the bulbular top of the stopper and to bring the slot opposite the glass neck.

It will be seen that by the use of this device the likelihood of infection of the liquid 25 within the container is reduced to a minimum.

Before the container is used for the sterile liquid, the bottle, cap and stopper may be sterilized in any desired manner, or the 30 sterilization may be performed after the liquid has been placed within the container.

While the stopper has been described as made of rubber, it will be evident that an equivalent material may be substituted 35 therefor. Such a material should be elastic so that a puncture will be closed upon the withdrawal of a needle and so that it will fit closely within the neck of the bottle and it must resist the heat necessary for the purpose of sterilization, while at the same time 40 it must be without chemical effect upon any of the liquids used for injection.

It will thus be seen that there has been provided a device possessing the particular features of advantage enumerated as desirable, 45 but which obviously is susceptible of modification in its form, proportions and details of construction without departure from the principle involved, or sacrificing of any of 50 its advantages.

It will therefore be understood that the invention is not limited to the specific details shown and it is therefore claimed in any of its forms or modifications within the 55 legitimate scope of the appended claims.

I claim:

1. A device for dispensing sterile liquids comprising a container, a stopper for the container consisting of a material adapted to permit the introduction therethrough of 60 a hypodermic needle, and a cap for said stopper having an antiseptic lining therein in contact with said stopper when the cap is in closed position.

2. A device as in claim 1, in which the cap 65 has a perforation free from the antiseptic lining, permitting the introduction of a hypodermic needle therethrough into said stopper when the cap is partially removed therefrom.

3. A device for dispensing sterile liquids, comprising a container having a screw threaded neck, a cap having a portion screw threaded for engagement with the neck, and a stopper adapted to fit in the mouth of the 75 container within said cap, said stopper being of a material permitting the introduction of a hypodermic needle therethrough, and said cap having an opening through a portion thereof which lies opposite the neck of the 80 container when the cap is in its closed position, and which lies opposite a portion of the stopper when the cap is partially unscrewed.

4. A device for dispensing sterile liquids comprising a container, a hollow rubber 85 stopper therefor, having a port communicating with the interior of the container and having a ball within its hollow interior adapted to be held by gravity to close said port and thereby to act as a valve to retain 90 liquid within the hollow stopper, and a cap adapted to be attached to the container and having an antiseptic pad lining its interior of a configuration to engage the outer surface of the rubber stopper when the cap is 95 in its closed position.

5. A device for dispensing sterile liquids comprising a container for said liquids, an aseptic closure for said container of a material capable of being punctured by a hypodermic needle, and a cover for said aseptic closure containing an antiseptic material in contact with said closure when the cover is in its closed position.

In testimony whereof I affix my signature 105 in presence of two witnesses.

GUSTAF A. PERSSON.
